UNITED STATES PATENT OFFICE.

JAMES F. MAGEE, OF SYRACUSE, NEW YORK, ASSIGNOR OF ONE-HALF TO LOUIS JOHNSONBECK, OF SYRACUSE, NEW YORK.

STROPPING DEVICE FOR SAFETY-RAZOR BLADES.

Application filed February 14, 1922. Serial No. 536,403.

To all whom it may concern:

Be it known that I, JAMES F. MAGEE, a citizen of the United States, and a resident of Syracuse, in the county of Onondaga and State of New York, have invented a certain new and useful Stropping Device for Safety-Razor Blades, of which the following is a specification.

This invention has for its object a stropping machine for safety razor blades, which is particularly simple and economical in construction and highly efficient and durable in use, and also which strops both sides of the same edge of the blade at the same time.

The invention consists in the novel features and in the combinations and constructions hereinafter set forth and claimed.

In describing this invention, reference is had to the accompanying drawings in which like characters designate corresponding parts in all the views.

Figure 1 is a plan view of this blade stropping machine.

Figure 2 is a side elevation thereof.

Figure 3 is a sectional view on line 3—3, Fig. 2.

Figure 4 is a sectional view on line 4—4, Fig. 1.

Figure 5 is an enlarged sectional view on line 5—5, Fig. 1.

Figure 6 is a view similar to Fig. 5 showing the jaws of the stropping element engaged with the blade.

Figure 7 is an end elevation looking to the left in Fig. 3.

Figure 8 is a detail view of the cam.

This stropping machine comprises generally, a frame or casing, a blade holding element, a stropping element, one of said elements being reciprocally movable toward and from the other parallel to the plane of the blade, means for reciprocating the reciprocally movable element and means for controlling the engagement and disengagement of the stropping element with the blade during such reciprocating movement.

1 designates the frame or casing which may be of any suitable form, size and construction, it being here struck up from sheet metal.

In the illustrated embodiment of my invention the stropping element is reciprocally movable and the blade holding element stationary.

2 designates the blade holding element and 3 the stropping element. The blade holding element, as here shown is a supporting strip or shelf supported at its ends in the side walls 4 of the casing 1 and a clamping or pressure device 5 for pressing the blade against the shelf. The clamping device is here shown as a spring clip arranged with its ends in slots or notches in the side walls 4 of the ends and its intermediate part 6 looped to form a handle. The arms 7 of the spring on opposite sides of the loop normally extend upwardly from the ends of the loop and the bends connecting the ends of the loop and the arms 7 are formed with bosses 8 arranged to enter the holes 9, in the razor blades 10 as Gillette blades or the slots of some other types of blades and hold the blades from movement on the shelf. However, studs may be provided on the support for entering the holes 9.

However, with other types of razor blades as shown in Fig. 5, formed with a single edge and with a folded back strip 11 the edge of one of the folds of the back 11 engages the rear edge of the shelf as at 12 and together with the spring 5 holds the blades from movement.

After the blade is placed on the support, the spring 5 is pressed into position, the spring arms 7 bending until they are below a dead center line passing through the point of engagement of the arms with a side wall 4 and the bend connecting said arms and the loop 6 of the spring. To remove the blades the spring is pulled upwardly by taking hold of the loop 6 until the bends connecting said arms 7 and the loop 6 passes above the dead center line.

The stropping element comprises a reciprocating carriage 13 and jaws carried by the carriage. The carriage 13 is a flat strip having its ends 12 slidable in the slots 15 in the opposite side walls 4 of the casing, and the jaws 14 are carried by spring arms 16 fixed at 17 to the carriage. The jaws are located above and below the plane of the blade held on the support 2. These jaws carrying strops 18 or other abrading members at their free ends. The spring arms 16 press the jaws toward each other onto the blade and press the strops against the upper and lower sides of the blade. The stropping element 3 is reciprocated by means

of a suitable crank shaft 19 journaled in the side walls 4 and connected to the carriage 13 by a link 20. The shaft 19 is provided with a suitable crank handle 21 at its 5 outer end.

The means for opening and closing the jaws comprises a cam or a pair of cams 22 slidably along the inner faces of the side wall 4, each cam being here shown as formed 10 with a slot 23 for receiving the end portion of the carriage 13, the cam having lift portions 24 which engage with laterally extending shoulders 25 at the end of the jaws 14.

15 The cams thus ride with the carriage 13 owing to the slot 23 and they are limited in their movement by stops in order to cause the lift portions to open the jaws after the jaws move out of engagement with the blade 20 and to hold the jaws open until the carriage is moved toward the blade into position to permit the jaws to close on the blade. Movement of the cams with the carriage 3 are limited in one direction by suitable stop 26 and in the opposite direction by the shaft 19 against which the rear ends of the cams strike after the jaws have passed off the blade.

During turning of the crank 21 the carriage 13 moves forwardly toward the blade, the lift portions 24 being under the lugs 25 of the jaws and holding the jaws separated until the jaws come above and below the blade whereupon the cams engage the stop 35 26 so that further movement of the cams with the jaws and carriage 13 is limited permitting the jaws during such further movement to close onto the blade.

Continued rotation of the handle 21 40 moves the carriage 13 and jaws in the opposite direction causing the strops which are now engaged with the blade to move off the end of the blade.

The cam moves with the jaws until it engages the shaft 19.

The cams engage the shaft 19 after the strops have moved off the edge of the blade so that during continued movement of the jaws in a retrograde direction the lugs 25 50 thereon engage the lift portions of the now stationary cams causing the jaws to separate. Continued movement of the handle 18 causes the open jaws and cam to move toward the blade until the cams are limited by the stop 26 as before.

This stropping machine is particularly advantageous in that it strops both sides of the same edge at the same time and thus creates a sharper or better cutting edge than 60 when such sides are stropped alternately.

It is further particularly advantageous in that it consists of a minimum number of compactly arranged parts.

What I claim is:

65 1. In a razor blade stropping machine, a

frame, a blade holder, a reciprocally movable stropping element having strops arranged to simultaneously engage opposite sides of the edge of the blade, means for reciprocating the stropping element, and 70 means for opening the stropping element to receive the blade during movement of said element in one direction and for closing said element on the blade during movement in the opposite direction, substantially as and 75 for the purpose set forth.

2. A razor blade stropping machine comprising a body, a blade holder carried by the body, a reciprocally movable stropping element movable parallel to the plane of the blade and including opposing jaws having strops for engaging opposite sides at the edge of the blade, means for reciprocating the stropping element, and means for opening the jaws during movement of the jaws toward the blade and for closing the jaws on the blade during movement of the jaws in the opposite direction, substantially as 80 and for the purpose described.

3. A razor blade stropping machine comprising a body, a blade holder carried by the body, a reciprocally movable stropping element including opposing jaws having strops for engaging opposite sides of the edge of the blade, means for reciprocating the stropping element, and means for opening the jaws during movement of the jaws toward the blade and for closing the jaws on the blade during movement of the jaws in the opposite direction, said means comprising a cam coacting with the jaws to open and close the same and operable by the stropping element, substantially as and for the purpose specified.

4. A razor blade stropping machine comprising a body, a blade holder carried by the body, a reciprocally movable stropping element including opposing jaws having strops for engaging opposite sides of the edge of the blade, means for reciprocating the stropping element, and means for opening the jaws during movement of the jaws toward the blade and for closing the jaws on the blade during movement of the jaws in the opposite direction, said means comprising a sliding cam extending between the jaws and coacting with the jaws to open and close the same and movable with the stropping element, and stops for limiting the movement of the cam with the stropping element before the stropping element reaches the limit of its movement in either direction, substantially as and for the purpose described.

5. A razor blade stropping machine comprising a frame, a blade holder carried by the frame, a reciprocally movable stropping element including opposing jaws having strops for engaging opposite sides at the edge of the blade, means for reciprocating

20

25

30

the stropping element, and means for opening the jaws during movement of the jaws toward the blade and for closing the jaws on the blade during movement of the jaws in the opposite direction, said means comprising a cam extending between the jaws and having lift portions arranged to coact with the jaws to separate the same, and to permit the jaws to close, and stops for limiting the movement of the cam with the jaws before the jaws reach the limit of their movement in either direction, substantially as and for the purpose set forth.

6. A stropping machine comprising a casting formed with slots in the side thereof, a blade holder, a reciprocating carriage guided in the slots and having jaws project-

ing toward the blade holder, the jaws being provided with strops on their opposing faces, a cam carried by the carriages and movable relatively thereto and having lift portions for coacting with the jaws, the cam being arranged in the path of the carriage and having its lift portions arranged in the paths of the jaws during retrograde movement of the jaws and stops for limiting the movement of the cam with the jaws in either direction, substantially as and for the purpose described.

In testimony whereof, I have hereunto signed my name, at Syracuse, in the county of Onondaga, and State of New York, this 29th day of July, 1921.

JAMES F. MAGEE.
